(57) **CLAIM**

The ornamental design for a corona ring, as shown and described.

DESCRIPTION

FIG. 1 is a front elevation view of the corona ring, showing my new invention;

FIG. 2 is a rear elevation view thereof;

FIG. 3 is a top plan view thereof;

FIG. 4 is a bottom plan view thereof;

FIG. 5 is a right side elevation view thereof;

FIG. 6 is a left side elevation view thereof; and,

FIG. 7 is a perspective view thereof.

The broken line portion of the drawings is included to show portions of the article that form no part of the claimed design.
